Application February 13, 1947, Serial No. 728,300

7 Claims. (Cl. 263--8)

1

The present invention relates to heat treating apparatus, and the primary object of the present invention is to provide improved apparatus for heating end portions of metallic rods and other elongated metallic articles. More specifically, the object of the invention is to provide simple and effective apparatus for rapidly and uniformly heating one end of each of rods or analogous elongated work pieces which are successively moved along a heating path in the course of which each work piece end to be heated is moved through the length of an elongated heating furnace chamber by an endless chain or belt conveyor alongside the furnace chamber. The chamber is formed with a slot in one side wall which forms a path for the movement of a portion of each work piece intermediate the end portion within the furnace chamber and the external portion of the work piece which is connected to the conveyor.

In its preferred form, the invention is characterized by the vertical disposition of the furnace chamber and by the arrangement of the chain conveyor so that the work pieces treated may be attached to successive upwardly moving portions of the conveyor so that each work piece end is moved into the furnace chamber at its upper end and is then moved downwardly through the furnace chamber. In its preferred form, the conveyor is arranged to permit each work piece to be discharged at the bottom of the furnace chamber by gravitational force as the portion of the conveyor chain previously supporting the work piece moves through a portion of its path of movement below the furnace and leading away from the vertical.

The invention is well adapted for use in heating ferrous bodies to forging temperatures and for other uses. For example, the invention is well adapted for use in heating brass tubes to annealing temperature.

The various features of novelty which characterize the invention are pointed out with particularity in the claims annexed to and forming a part of this specification. For a better understanding of the invention, however, its advantages and specific objects attained with its use, reference should be had to the accompanying drawing and descriptive matter in which we have illustrated and described a preferred embodiment of the invention.

Fig. 1 is an elevation of a continuous furnace and its conveyor mechanism;

Fig. 2 is an elevation taken at right angles to Fig. 1;

2

Fig. 3 is an elevation taken similarly to Fig. 2, but showing the furnace structure only;

Fig. 4 is a section on the line 4—4 of Fig. 3;

Fig. 5 is a plan view of the furnace structure shown in Figs. 3 and 4; and

Fig. 6 is a section on the line 6—6 of Fig. 4.

The apparatus shown in the drawings comprises a base structure A which supports a vertically elongated furnace structure B, and an associated conveyor mechanism comprising a supporting framework C alongside the furnace structure B and extending between upper and lower levels, respectively above and below the top and bottom of the furnace structure. 10 Mounted in the framework C is a conveyor mechanism comprising two side by side link belts or chain conveyors D, each running over a separate set of sprocket wheels E¹, E², E³ and E⁴. Each of the sprocket wheels is mounted on 20 and secured to a corresponding shaft journalled in the supporting framework and on which the corresponding sprocket wheel of the other set is mounted and secured. As shown, the endless sprocket chains are kept moving continuously 25 in the direction indicated by the arrows in Figs. 1 and 2, by a driving motor F suitably connected through a variable speed driving mechanism G to one of the sprocket wheel shafts. As shown that shaft is the one which carries the sprocket wheels E³, as well as a sprocket wheel E⁵. The latter is connected by a sprocket chain belt G' to the output sprocket wheel G² of the driving mechanism G. The latter is driven by the motor F through a belt F' running over a pulley F² 30 carried by the motor shaft and over the input pulley wheel G³ of the driving mechanism. 35

As shown, the framework C may include adjusting means FA for vertically adjusting the shaft carrying the sprocket wheels E⁴, so as to avoid undesirable slackness in the conveyor chains D. A pivoted belt tightening lever E⁶ carrying an idler E⁷ at one end which is in engagement with the sprocket chain G', keeps the latter sufficiently taut. The belt F' may be kept under suitable tension by an adjusting mechanism F³ of conventional form for bodily adjusting the motor F toward and away from the variable speed drive unit G. Each sprocket chain D is provided with work holders D' distributed at suitable intervals 40 along the length of the sprocket chain. Each pair of work holders D' carried by the two sprocket chains D in end to end relation with one another constitutes a work support for a horizontally disposed bar or other elongated work 45 piece d. The latter may be put in place in the two 50

work supports while they are moving upwardly at the left side of the supporting framework C, as seen in Fig. 2, through a convenient loading level which may be that of the top of the base structure A. Each work piece thus mounted in a pair of work holders, is carried by the latter upward to, and thence over sprocket wheels E¹, and thence to and over sprocket wheels E², and thence down to and through the level of the axis of the sprocket wheels E³. As each pair of work supports D passes below the level of said axis and thence toward the under side of the sprocket wheels E⁴, its path of movement is inclined to the vertical and the work supports are inverted sufficient to permit the work piece previously held in the work supports to move out of the latter under the action of gravity. Each work piece d thus discharged, falls into a downwardly inclined chute or guideway H through which the work pieces successively heated in the furnace B pass away from the heat treating apparatus shown in the drawings.

The work holders D' may take various forms. In the simple form shown, each work holder D' comprises a link of the corresponding sprocket chain D, provided adjacent each end with a rib D² extending outwardly away from the chain. The outer end portion of each rib D² is bent toward the other rib so that the body of the link and the two ribs form a C-shaped saddle or undercut seat in which a work piece is securely held by gravity until the work supports are partly inverted. In the particular construction shown, each link of each conveyor chain D is formed with a pair of ribs D² and constitutes a work holder D'. To insure the discharge of each of the successively advanced work pieces at exactly the same discharge level, stationary retaining devices D³, one adjacent each chain D, are disposed to hold each work piece in the corresponding pair of work holders until their rear ribs begin to move horizontally away from the retaining device D³. The devices D³ are attached to the framework C and cause both ends of each work piece to leave the corresponding work holders at about the same time.

The furnace structure B is formed with a vertically extending furnace chamber B' which is open at its ends. The wall of the chamber B', adjacent the descending portion of the conveyor, is formed with a slot B² open at its ends and through which each work piece d moving downward from the sprocket wheels E² to the sprocket wheels E³, extends into the furnace chamber.

The form and dimensions of the furnace chamber B' and its heating means may vary with the conditions of use. The particular furnace structure shown by way of example in Figs. 1 and 2 was devised with particular reference to use in heating the ends of work pieces d in the form of round bars of ferrous material about six feet long and about seven-eighths of an inch in diameter, to a temperature of approximately 2250° F., preparatory to the subjection of the heated end of the bar to a forging operation, such as that required to adapt the bar for use as an automobile sway-bar. The main lower portion of the particular furnace chamber B', shown by way of example, is rectangular in cross-section with a horizontal length of about 10 or 11 inches and a breadth of 5 or 6 inches, and the masonry wall of the chamber in which the slot B² is formed may be about 3 inches thick, and the slot itself may be somewhat less than 2 inches wide.

The chamber B' is shaped to form an entrance

space above the main lower heating space and of somewhat smaller cross-section. A plurality of distributed furnace wall burners I are incorporated in each of the opposing side walls of the main lower portion of the heating chamber B'. In the particular furnace form shown, the burners in each side wall of the chamber B' are arranged in two side by side rows with seven burners in each row, and each of those burners is advantageously of the well known and widely used type disclosed in Hess Patent No. 2,215,079, of September 17, 1940. Such a burner is characterized by the supply of a combustible mixture of air and gas to a shallow cup-shaped combustion chamber I' in fine streams distributed about the combustion chamber axis and so directed that combustion is effected at the surface of the combustion chamber and heats the ceramic wall of the combustion chamber to a high temperature so that it emits a relatively large amount of radiant heat. Combustible mixture is supplied to each burner through an individual supply passage I² extending from the combustion chamber I' of the burner to the adjacent side wall of the furnace structure and receiving a combustible mixture of air and gas through external piping which may be arranged and associated with valves for regulating the supplies to the different burners in the manner now customarily employed in gas fired furnaces having a multiplicity of distributed furnace wall burners.

The furnace structure B may be formed of refractory material encased in sheet metal, and the sheet metal casing may be reenforced by channel bars or the like in accordance with usual practice. The particular ceramic materials used in the furnace structure will ordinarily depend on the temperatures attained in the corresponding portions of the furnace structure. The furnace structure proper may well be jacketed with insulating material to improve the thermal efficiency of the furnace and to avoid undesirable heating of the space surrounding the apparatus. To minimize the heating effect of the furnace on the supporting structure A, water walls J are provided at the bottom of the furnace, and water walls J' are provided at the side of the furnace facing the conveyor mechanism.

To minimize the chimney stack action of the furnace, the opening at the upper end of the furnace chamber B', through which the ends of the work pieces d are moved downward into the furnace chamber, is made as small as is practically possible by the use of metal plates K and K'. The plates K and K' are arranged at the opposite sides of the slot-like space through which the ends of the work pieces pass downward to the furnace chamber B' and slot B². Each of the plates K and K' may be adjusted toward and away from the other by means of a corresponding bolt and nut connection K⁴ between the cover plate and a bracket K³ anchored to the furnace structure. The cover plate K² limits the length of the open space between the adjacent edges of the cover plates K and K', and is adjustable to vary the length of said space by means of a threaded connection K⁴ between the plate K² and a bracket K³ suitably anchored to the furnace structure.

As shown, the actual width of the outer edge of the vertical slot through which the work pieces d extend into the furnace chamber, is fixed by the adjustment of cover plates L and L' which may be formed of stainless steel and rest against the chamber cooling walls J' at the side

of the furnace structure facing the conveyor mechanism. The distance between the adjacent edges of the cover plates L and L' need be but a trifle greater than the diameter of the work piece portions passing between those edges, as is shown in Fig. 6.

In the contemplated use of the apparatus shown in the drawings, a work piece *d* is seated in each work support formed by an end to end pair of work holder elements D' of the conveyor chains D, as said work holders pass through the work charging or loading level. That level may be the level of the top of the base A or any other convenient level. The work pieces may be manually placed in the work holders. Except for the insertion of the work pieces in the work holders, the operation of the apparatus shown is purely automatic and continuous. With burners of the type described and arranged at the opposite sides of the heating chamber B', as shown, the heating operation is rapid and uniform. A rod end of the dimensions stated above, by way of example, may be heated from atmospheric temperature to a temperature of 2250° or so, during a period of about four and one-half minutes in which the end moves from the top of the furnace chamber B' to its lower end. This means that if the combustion chamber length is 6 feet, the linear travel of the belt may be about one and one-third feet per minute, and if each belt link serves as a work holder and is two inches long, heated rods will be discharged from the apparatus at the rate of eight pieces per minute, or 480 pieces per hour.

With the vertical disposition of the furnace chamber and the movement of the work pieces downward through the furnace chamber, as the hot products of combustion move upward from the level of the uppermost burner I to the top of the furnace, they give up much of their heat to the work pieces which are cold when they enter the furnace chamber. This preliminary heating of the work pieces in the entrance portion of the furnace chamber not only increases the thermal efficiency of the furnace, but helps to avoid overheating the space surrounding the heat treating apparatus.

As will be apparent to those skilled in the art, the temperature of 2250° mentioned above is a typical forging temperature for ferrous metals, and apparatus of the character shown in the drawings is of a special utility in heating small work pieces of the character mentioned above to forging temperatures, because of the uniformity of the heating operation and the rapidity with which it is effected. That rapidity contributes directly to a reduction of the amount of scale formed in the furnace. Furthermore the scale formed as the work pieces move downwardly through the furnace chamber and not adhering to the work pieces, is free to fall downward through the furnace chamber and out through the open lower end of the latter. Moreover, much of the scale adhering to the work pieces as they reach the discharge level, is dislodged and separated from the work pieces as the latter fall out of the work holders on to the discharge guides and roll down the latter. In forging operations, the uniform heating of the work to the proper forging temperature, and the reduction of the scale on the work pieces to a minimum, are two elements of the operation contributing materially to the efficiency and low cost of the forging operation. A major cost item in the forging of small ferrous bodies is

the cost of forging die and the cost of die repairs and replacements. Another substantial cost item is the loss of forged products, which, because of improper heating, are inferior and must be treated as scrap.

While the invention has special advantages for use in heating ferrous work pieces to a forging temperature, it may also be used for many other purposes. In particular, it may be used in annealing ferrous and non-ferrous metallic bodies at temperatures substantially lower than forging temperatures and may be of the order of 1400° F. to 800° F., respectively.

While in accordance with the provisions of the statutes, we have illustrated and described the best form of embodiment of the invention now known to us, it will be apparent to those skilled in the art that changes may be made in the form of the apparatus disclosed without departing from the spirit of the invention as set forth in the appended claims, and that in some cases certain features of the invention may be used to advantage without a corresponding use of other features.

What is claimed is:

- Heat treating apparatus comprising structure providing a vertically extending refractory lined chamber having end openings at the top and bottom and a slotted side wall, conveyor means adjacent to said chamber for carrying and vertically transporting horizontally disposed elongated work pieces to be heated at an end thereof, said conveyor means being positioned with respect to said structure so that the ends of the work pieces to be heated project into the chamber through the slotted wall thereof during vertical transport and enter and leave the chamber through the end openings and scale formed on the ends of the work pieces during heating thereof will freely fall downwardly through the chamber and pass therefrom through the bottom and opening, means to drive said conveyor means in a direction to move said work pieces downwardly through said chamber, and means for directly heating said chamber comprising opposed burners incorporated and distributed in the refractory lining thereof, on sides adjacent to the side of said chamber having said slot therein, the portion of the work pieces projecting into said chamber being in between the opposed burners, to heat the ends of the work pieces during transport through the chamber to an elevated temperature suitable for forging and like forming operations.
- Heat treating apparatus comprising structure providing a vertically extending refractory lined chamber which is open at the top and bottom and slotted at a side wall thereof, opposed burners located in the side walls of said chamber at right angles to the side having said slot, conveyor means adjacent to said chamber for carrying and vertically transporting in spaced apart relation horizontally disposed elongated work pieces to be heated at an end thereof, said conveyor means being positioned with respect to said structure so that the ends of the work pieces to be heated project into the chamber through the slotted wall thereof and in between the burners during vertical transport and enter and leave the chamber through the openings at the top and bottom, respectively, means to drive said conveyor means in a direction to move said work pieces downwardly through said chamber, means for firing said chamber to an elevated temperature, said conveyor means including C-

shaped members which support the elongated work pieces during downward vertical transport through said chamber and tilt downwardly at the open sides thereof after leaving the chamber for discharging heated work pieces therefrom by gravity.

3. Heat treating apparatus as set forth in claim 2 including chute means to receive the elongated work pieces from the conveyor means.

4. Heat treating apparatus comprising structure providing a vertically extending refractory lined chamber having end openings at the top and bottom and a slotted side wall, conveyor mechanism adjacent to said chamber for carrying and vertically transporting in spaced apart relation horizontally disposed elongated work pieces to be heated at an end thereof, said conveyor mechanism being positioned with respect to said structure so that the ends of the work pieces to be heated project into the chamber through the slotted wall thereof during vertical transport and enter and leave the chamber through the end openings, means for firing said chamber to an elevated temperature comprising burners positioned in the side walls of said chamber adjacent to the side having said slot therein and between which the sides of the portion of the work projected into said chamber are located, and means to drive said conveyor mechanism to transport the work pieces downwardly through the chamber, said conveyor mechanism including means operable to discharge the work pieces therefrom after the latter pass from the bottom opening of the chamber.

5. Heat treating apparatus comprising structure providing a vertically extending refractory lined chamber which is open at the top and bottom and slotted at a side wall thereof, means for firing said chamber to an elevated temperature comprising opposed burners in the side walls of said chamber adjacent to the side having said slot therein, conveyor means adjacent to the chamber including an up-run side and a down-run side for carrying and vertically transporting in spaced apart relation horizontally disposed elongated work pieces to be heated at an end thereof, said conveyor means being positioned with respect to said structure so that the ends of the work pieces to be heated project into the chamber through the slotted wall thereof and in between said burners, means to drive said conveyor means in a direction so that said work pieces enter and leave the chamber through the openings at the top and bottom, respectively, the down-run side of the conveyor means including a sloping portion at a level below the bottom opening at which region the elongated work pieces are adapted to fall by gravity from the conveyor means, chute means to receive the elongated work pieces from the conveyor means, and work piece retaining means arranged to engage the elongated work pieces in the region in which the latter fall from said conveyor means to cause both ends of each heated work piece to

leave the conveyor means at about the same time.

6. Heat treating apparatus comprising structure providing a vertically extending refractory lined chamber having end openings at the top and bottom and a slotted side wall, conveyor means adjacent to said chamber for carrying and vertically transporting elongated work pieces to be heated at an end thereof, said conveyor means being positioned with respect to said structure so that the ends of the work pieces to be heated project into the chamber through the slotted wall thereof during vertical transport and enter and leave the chamber through the end openings, means for firing said chamber to an elevated temperature, comprising opposed burners positioned in the walls of said chamber adjacent to the wall having said slot therein and between which opposite sides of the portions of the work pieces projecting into said chamber are located as they move through said chamber, and means comprising movable members at the top of said structure at the vicinity of the end opening for adjusting the size of such opening to accommodate work pieces of different size.

7. Heat treating apparatus comprising structure providing a vertically extending refractory lined chamber having end openings at the top and bottom and a slotted side wall, conveyor means adjacent to said chamber for carrying and vertically transporting elongated work pieces to be heated at an end thereof, said conveyor means being positioned with respect to said structure so that the ends of the work pieces to be heated project into the chamber through the slotted wall thereof during vertical transport and enter and leave the chamber through the end openings, means for firing said chamber to an elevated temperature, comprising burners positioned opposite the ends of the work pieces as they move through said chamber, vertically extending hollow jackets at the side wall at opposite sides of the slot therein, said jackets having inlets and outlets for circulating a coolant there-through, and means including adjustable plate members overlying said jackets for varying the width of the gap formed therebetween at the region of the slot.
